UNITED STATES PATENT OFFICE.

HARRY A. TAYLOR, OF NEW YORK, N. Y.

GLOVE.

1,153,728.

Specification of Letters Patent. Patented Sept. 14, 1915.

Application filed January 12, 1914. Serial No. 811,515.

To all whom it may concern:

Be it known that I, HARRY A. TAYLOR, a citizen of the United States, and a resident of the city of New York, borough of Manhattan, county and State of New York, have invented certain new and useful Improvements in Gloves, of which the following is a specification.

My invention relates broadly to new and useful improvements in gloves, and more particularly to gloves made from either knitted or woven textile fabrics.

It is well known that in nearly all gloves the thumb is formed from a blank separate from the blank from which the hand portion and fingers of the glove are formed, and such thumb blank is united to the body of the glove by a seam passing from between the thumb and index finger on the back of the glove around the base of the thumb to a point either in the palm, or at a point between the thumb and the index finger on the front or palm portion of the glove. This seam is objectionable, particularly in the case of tight fitting gloves, because the seam stretches less than the body of the glove so that when the glove is worn the seam presents a ridge, causing the base of the thumb to have an unsightly swollen or puffed appearance.

It is, therefore, the primary object of this invention to provide a glove in which the portion from which the thumb is formed will be integral with the front and back of the glove, whereby the usual seam above mentioned is obviated, and which at the same time will be slightly in appearance, and which will shape itself properly to the hand of the wearer so that the swollen or puffed appearance of the thumb above mentioned will be obviated.

The invention consists in the improvements to be more fully described herein-after, and the novelty of which will be particularly pointed out and distinctly claimed.

I have fully and clearly illustrated my invention in the accompanying drawings to be taken as a part of this specification, and wherein—

Figure 1 is a plan view of a palm face of a glove made in accordance with my invention, showing the rear and side portions of the thumb. Fig. 2 is a detailed view similar to Fig. 1, but showing the thumb bent back to show the inner face thereof, and the entire palm. Fig. 3 is a plan view of a

preferable form of blank from which the glove is made. Fig. 4 is a detailed view of an insert for forming a portion of the palm, and the inner face of the thumb of the glove. 60

Referring to the drawings by characters of reference, 1 designates in general a glove embodying my invention and having a back 1^a, fingers 2, palm 3, and wrist portion 4, the latter having the closure 5 adapted to be secured about the wrist of the wearer by any suitable form of fastener indicated generally at 6.

7 designates the thumb of the glove, the back 8 of which, it will be noted, is formed at its base integral with the blank from which the back, palm and wrist are formed, the thumb being formed by said back portion 8 and an inner portion 9, the back and inner portions being united by side stitch 70 lines 10, 10^a. The blank 9 forming the inner face of the thumb terminates preferably at the crotch between the thumb and index finger where it is joined by a line of stitches 11 to the base of the triangular insert piece 80 12, the sides of said triangle being stitched to the palm face of the glove by stitch lines 13, 13^a, and the apex 14 of said triangular piece terminating at the juncture between the index finger and the middle finger. 85

Having briefly described the general construction of the completed glove, I will now describe the blank from which it is made and the manner of making the glove from said blank. The blank from which the glove is 90 made is shown in Fig. 3, and in this figure the body of the blank is shown as embodying a side section 15, an intermediate section 16, and a second side section 17, which sections are adapted to be folded over on the intermediate section along the dotted lines 18, 19, to form the palm of the glove and the inner faces of the fingers, the intermediate section 16 constituting the back of the glove. The side section 15 is formed with a thumb 100 projection 20, and a finger section 21, while the intermediate section is formed with a finger section 21^a adapted to be united by stitch lines along the edges thereof to the section 21 to form the index finger. The 105 section 16 is also formed with finger sections 22, 23 and 24 to form the backs of the middle, third and little fingers. The side section 17 is formed with a finger section 24^a at the side next the fold line 19, with 110 a finger section 22^a at its outer edge, and with an intermediate finger section 23^a,

which finger sections 22^a, 23^a and 24^a, when the side section 17 is folded over on the line 19, cover respectively the finger sections 22, 23 and 24 on the intermediate section 16, and form the inner faces of the middle, third and little fingers. It will be understood that the front and rear finger sections of each finger may be connected with fourchettes 25, as shown in Fig. 1, or may be stitched directly to each other, as would be the case in the cheaper types of gloves. When the side sections 15, 17 are folded over on the intermediate section 16, the side line 15^a of the thumb section 15, and the side line 17^a of the section 17, form at the lower portion of the glove the edges of the wrist flaps, and at the intermediate portion are united along a stitch line 26 located in the palm of the glove, the said stitch line 26 terminating at the point 27, which, when the glove is on the hand, is at the juncture between the base of the index finger and the inner edge of the thumb, from which point the edge 17^a passes along the stitch line 13^a to the point of juncture between the index and middle fingers, and thence on along the seam uniting the front and back finger sections 22, 22^a of the middle finger. From the point 26 the edge 15^a of the section 15 passes along the inner edge of the thumb section 20, and is stitched thereto along the line 10^a above described.

When the side edge portion of the blank part 15 is folded over along the line 18 the outer edge of the finger section 21 is in a position for a portion of its length from the end of the finger to be sewed to the inner edge of the finger section 21^a, while the remaining portion of the outer edge of the finger section 21 takes a position corresponding to the stitch line 13, extending from the juncture between the index and middle finger to the base of the thumb. In order to fill the space between the edges 13, 13^a, and to close the inner face of the thumb and complete the latter, I provide a substantially diamond-shaped piece, such as shown in Fig. 4, preferably consisting of the two sections 9, 12, united by the stitch

line 11 set on the bias of the longitudinal axis of said insert for a purpose to be presently described. When the glove is completed this insert is stitched to the edges 13, 13^a, and the side edges of the thumb piece 20, thereby completing the thumb and the palm of the glove. By having the insert in two pieces united by the bias line of stitches, a snug and sightly fit of the glove is provided at the portion of the palm between the forefinger and the thumb.

What I claim and desire to secure by Letters Patent of the United States is:

1. A glove made from a blank comprising an intermediate portion constituting the back of the glove and back finger sections, and two side portions constituting the palm of the glove and palm finger sections, one of said side portions having a part integral therewith forming the back of the thumb, said side portions being folded over on the back portion and united to form the fingers and a portion of the palm, and a substantially diamond-shaped insert forming the inner portion of the thumb and completing the palm.

2. A glove made from a blank comprising an intermediate portion constituting the back of the glove and back finger sections, and two side portions constituting the palm of the glove and palm finger sections, one of said side portions having a part integral therewith forming the back of the thumb, said side portions being folded over the back of the thumb and united to form the fingers and a portion of the palm, and an insert forming the inner portion of the thumb and completing the palm, said insert being substantially diamond-shaped and extending lengthwise of the palm to a point at the juncture of the index and middle fingers.

In testimony whereof I have hereunto signed my name in the presence of two subscribing witnesses.

HARRY A. TAYLOR.
